US0D1087010S

(12) **United States Design Patent** (10) **Patent No.:** **US D1,087,010 S**
(45) **Date of Patent:** **** Aug. 5, 2025**

(54) **FOLDABLE CHARGING STAND**

(71) Applicant: **SARIANA, LLC**, San Diego, CA (US)

(72) Inventors: **Alan Turksu**, San Diego, CA (US);
Mustafa Burak Guclu, San Diego, CA (US)

(73) Assignee: **SARIANA LLC**, San Diego, CA (US)

(**) Term: **15 Years**

(21) Appl. No.: **29/880,249**

(22) Filed: **Jul. 19, 2023**

(51) **LOC (15) Cl.** **13-02**

(52) **U.S. Cl.**
USPC **D13/108**

(57) **CLAIM**

The ornamental design for a foldable charging stand as shown and described.

DESCRIPTION

FIG. 1 is a top, front, and left perspective view of a foldable charging stand showing our new design in a first position; FIG. 2 is a bottom, rear, and right perspective view thereof; FIG. 3 is a front elevational view thereof; FIG. 4 is a rear elevational view thereof; FIG. 5 is a top plan view thereof; FIG. 6 is a bottom plan view thereof; FIG. 7 is a left side elevational view thereof; FIG. 8 is a right side elevational view thereof; FIG. 9 is a top, front, and left perspective view of the foldable charging stand shown in a second position; FIG. 10 is a bottom, rear, and right perspective view thereof; FIG. 11 is a left elevational side view thereof; FIG. 12 is a top, front and left perspective view of the foldable charging stand shown in a third position and in an environment of use; FIG. 13 is a top, rear, and right perspective view of the foldable charging stand shown in the third position; and, FIG. 14 is a top, rear, and right perspective view of the foldable charging stand shown in the third position and in an environment of use.

The broken lines showing the mobile phone and charging case in FIGS. 12 and 14 depict environments of use and all other broken lines depict portions of the foldable charging stand that form no part of the claimed design.

1 Claim, 14 Drawing Sheets
